UNITED STATES PATENT OFFICE.

ARTHUR EAVES, OF FALL RIVER, MASSACHUSETTS, ASSIGNOR TO DRAPER COMPANY, OF HOPEDALE, MASSACHUSETTS, A CORPORATION OF MAINE.

PICKER-CHECKING MEANS FOR LOOMS.

SPECIFICATION forming part of Letters Patent No. 729,048, dated May 26, 1903.

Application filed October 17, 1902. Serial No. 127,670. (No model.)

To all whom it may concern:

Be it known that I, ARTHUR EAVES, a citizen of the United States, and a resident of Fall River, county of Bristol, State of Massachusetts, have invented an Improvement in Picker-Checking Means for Looms, of which the following description, in connection with the accompanying drawings, is a specification, like characters on the drawings representing like parts.

This invention relates more particularly to picker-checking means for looms; and it has for its object the production of novel and simple means for very effectively checking the outward movement of the picker when the shuttle enters the shuttle-box.

The various novel features of my invention will be fully described hereinafter and particularly pointed out in the following claims.

Figure 1 is a front elevation of one end of the lay of a loom and the shuttle-box thereon with one embodiment of my invention applied thereto. Fig. 2 is a top or plan view of the mechanism shown in Fig. 1. Fig. 3 is a top or plan view of the shuttle-binder detached to more clearly show the picker-check carried thereby, and Fig. 4 is a rear elevation of the binder and picker-check.

The lay A³, having a shuttle-box thereon comprising a front plate b, back plate or wall b', shuttle-guard or top plate b², the binder B^X, pivotally mounted near its outer end upon the lay at b^X, the spring-controlled protector-shaft p, and the upturned finger p², carried thereby and bearing against the free inner end of the binder, may be and are all of usual or well-known construction and operate in the usual manner. The lay is shown as longitudinally slotted at A^X, Fig. 2, for the staff 40 of the usual picker P.

As shown in Fig. 2, the swell 2 of the binder extends into the path of the shuttle when the latter is not in the box, and the impact of the entering shuttle throws or swings the free end of the binder out against the usual spring, (not shown,) the greater the impact of the shuttle upon the binder the greater the outward movement of the latter. In accordance with the illustrated embodiment of my present invention this shuttle-induced movement of the binder is made effective to

actuate a picker-check and therethrough check the outward throw of the picker, thus preventing rebound of the shuttle in the box.

The picker-check is shown as an elongated hook-like member c' the side c' thereof being bent at c² c³ and secured to the back face of the binder by suitable means, as screws 5, Fig. 4, so that the side c extends longitudinally parallel to and preferably just within 60 the path of movement of the outer side of the picker P, so that there will be frictional engagement therebetween.

I prefer to make the check resilient, and it is conveniently made of a metal strap of req- 65 usite size and stiffness, the inner end of the side c of the check being bent out or flared, as at c^X.

As shown clearly in Figs. 1 and 2, the member c' extends beyond the outer pivoted end 70 of the binder to afford ample room for the movement of the picker and presents a horizontal U-shaped hook, into which the picker enters on its outward throw, the distance between the sides c' being great enough to prevent the side c' from engaging the rear face or side of the picker. When the incoming shuttle strikes the swell 2 of the binder, the latter is thrown outward, swinging on its fulcrum b^X, and the checking member is moved 80 thereby, so as to project the side c thereof a greater or less distance inward within the path of the front side or face of the picker, the flared inner end c^X of the check member c first engaging the picker on its outward 85 stroke. The pressure thus exerted upon the picker by engagement with the check acts to frictionally retard and check the picker, so that it will gradually slow down as it reaches the end of its outward stroke, the resiliency 90 of the check permitting it to flex as the picker moves along.

It will be obvious that the greater the impact of the entering shuttle upon the binder the greater will be the quick outward throw 95 of the latter, and consequently the greater will be the pressure exerted upon the picker by my novel picker-check, the pressure or retarding action exerted thereby thus being proportional to the speed of the incoming 100 shuttle.

By engaging only one side of the picker

there is no wedging action upon it, and it is the more readily and quickly freed when the shuttle is thrown from the shuttle-box.

Having fully described my invention, what 5 I claim as new, and desire to secure by Letters Patent, is—

1. In a loom, the lay having a shuttle-box, a binder, a picker, and an elongated hook-like friction-check mounted on the binder, 10 shuttle-induced movement of the binder causing the check to engage the picker with a pressure proportional to the force with which the incoming shuttle strikes the binder.

2. In a loom, the lay having a shuttle-box, 15 a binder, a picker, and an elongated, resilient checking member fixedly mounted upon the binder and longitudinally extended adjacent and substantially parallel to the path of movement of the picker, said checking 20 member being brought into operative engage-

ment with the outer side of the picker by or through shuttle - induced movement of the binder.

3. In a loom, the lay having a shuttle-box thereon, a spring-controlled binder fulcrum²⁵ near its outer end upon the lay, a picker, and a resilient, hook-like picker-check mounted upon the binder at its outer end and extended inwardly adjacent the path of movement of the picker, shuttle-induced movement of the binder acting to force the check against the picker.

In testimony whereof I have signed my name to this specification in the presence of two subscribing witnesses.

ARTHUR EAVES.
